HOOD HINGE

Joseph Soss, Roselle, N. J.

Application October 12, 1934, Serial No. 747,997

9 Claims. (Cl. 16—128.1)

This invention relates to hinges for the hoods of motor vehicles; and the object of the invention is to provide a hinge of this class consisting of two elongated sheet metal parts having spaced 5 interfitting pintle bearing portions with a pintle pin disposed therein for coupling and hingedly mounting the parts together; a further object being to provide a hinge of this class wherein one of the butt parts includes an integral hood portion 10 extending continuously throughout the length thereof and concealing the joint of the hinge and also forming a finishing strip between adjacent surfaces of the members coupled together by said hinge; a further object being to 15 provide the pintle pin of the hinge with large end portions facilitating the attachment of the pin to suitable supports, and further to the provision of a pin composed of separate parts having a sliding coupling therebetween to properly align 20 the bracket ends of the pin with respect to the supports and to provide attachment and detachment of the butt parts by the removal of said pin; and with these and other objects in view, 25 the invention consists in a hinge of the class and for the purpose specified, which is simple in construction, efficient in use, and which is constructed as hereinafter described and claimed.

The invention is fully disclosed in the following specification, of which the accompanying 30 drawings form a part, in which the separate parts of my improvement are designated by suitable reference characters in each of the views, and in which:

Fig. 1 is a plan and sectional view of a hinge 35 made according to my invention, indicating the method of its use and with part of the construction broken away.

Fig. 2 shows sectional views through the separate parts of the hinge shown in Fig. 1 in detached relation.

Fig. 3 is a view similar to Fig. 2 showing the hinge parts coupled together, the section being on the line 3—3 of Fig. 1.

Fig. 4 is a section on the line 4—4 of Fig. 1.

Fig. 5 is a view similar to Fig. 2 showing modified forms of hinge butts.

Fig. 6 is a section along the same line as Fig. 3 but showing the parts illustrated in Fig. 5 in 50 assembled relationship.

Fig. 7 is a section of the hinge parts shown in Figs. 5 and 6 along the line similar to that shown in Fig. 4.

Fig. 8 is a sectional view showing a modified 55 form of hinge.

Fig. 9 is an inside plan view of a part of a member shown in Fig. 8.

Fig. 10 is a sectional detail view of one butt member shown in Fig. 4 and showing a modification.

Fig. 11 is a view similar to Fig. 3 showing another modified form of construction; and,

Fig. 12 is an end view of the pintle pin employed.

In my prior Patent #1,743,495, dated January 14, 1930, I disclosed a hinge composed of two sheet metal parts having interfitting pintle bearing portions, one of the parts being shaped to form a hood. My present invention consists in an improvement on said prior patent wherein the 10 hinge butt parts are so constructed as to form an elongated hinge designed primarily for use as a means for joining the separate parts of an automobile hood together, or in other words, to produce what is known as a hood hinge.

In the drawings, 10 and 11 represent the adjacent edge portions of the separate parts of a hood to be coupled together by one of my improved hood hinges 12. The hinge consists of 20 separate parts or two members 13 and 14 having 25 extending attaching plate portions 15 and 16 respectively for attachment to inwardly and downwardly projecting flanges 10a, 11a of the hood parts 10 and 11. Each of the butt members 13 and 14 consists of elongated strips of sheet metal 30 of a length substantially equal to the length of the adjacent edges of the hood parts 10 and 11.

The part 13 is fashioned to form an upwardly or outwardly projecting curved hood portion 17, 35 within which is an inwardly or downwardly directed semi-cylindrical pintle bearing portion 18 formed as an extension to the edge 17a of the hood 17 in the offset shoulder portion 19, and the end 20 of the strip rests upon and is secured to the other side of the hood portion 17 40 by welding or in any other desired manner. The pintle bearing 18 is cut out at intervals as is indicated at 21 to receive the cylindrical bearings 22 formed at one side of the strip from which the butt member 14 is formed. It will appear from 45 a consideration of Figs. 3 and 4 of the drawings that the cylindrical pintle bearing 22 is disposed in alignment with the semi-cylindrical bearing 18 so as to receive the pintle pin 23, said pin seating in both of the bearings 18 and 22.

The bearing 22 joins the attaching plate 16 in an arc-shaped portion 24 having a radial end 25 which provides a clearance space 26 between the bearing 22 and the arc-shaped portion 24 in which the offset end 17a of the butt part 17 is 50 55

adapted to operate as the separate hood parts 10 and 11 are moved into open position in the manner indicated in dotted lines in Fig. 3 of the drawings. The butt member 14 has the bearings 22 arranged in spaced relation to each other longitudinally thereof to receive the spaced bearings 18 of the butt member 13. One of the spaces is indicated by the cut out 25a in Fig. 4 of the drawings.

10 It will be understood that a single or unitary pintle pin 23 may be employed, in which event, it will include at one end an integral bracket portion 23a, note Fig. 12 of the drawings, by means of which the pin may be secured to a suitable support. In the construction shown, however, the pin is made of separate parts 23b and 23c having a tongue and groove or other sliding connection as is indicated at 23d. At 23e I have shown an integral bracket at the free end of the part 23c. By means of the sliding coupling between the parts 23b and 23c, the bracket ends 23a and 23e may be fitted to spaced supports 27 and 28 as indicated in Fig. 1 of the drawings. At the same time, the pintle pin or the separate parts thereof may be readily detached from the hinge butts in coupling and uncoupling the same. The bracket ends 23a, 23e will be formed by simply flattening the ends of the rod forming the pintle pin, thus providing a very simple and economical construction. This will avoid the use of the conventional mounting brackets commonly employed as supports for hinges of the class under consideration.

In Figs. 5, 6 and 7, I have shown a slight modification wherein a butt member 29 similar to the butt member 13 is employed and a butt member 30 similar to the butt member 14. The primary difference between the butt members in the two hinges is that the butt member 29 includes a double hood wall 31 instead of the single wall shown in Figs. 1 to 4 inclusive, the inner wall being cut and pressed downwardly or inwardly at intervals to form spaced semi-cylindrical bearings 32 equivalent to the bearings 18.

45 The butt member 30 differs from the member 14 in that the ends of the sheet forming the cylindrical bearing 33 are extended to form a spacing or offset member 34 of double wall thickness and a curved or arc-shaped portion 35 of double wall thickness instead of single walls 25, 24 of like parts shown in Figs. 2 to 4 inclusive. With this construction, it will appear that the attaching plate portion 29a of the butt 29 is of double wall thickness, and the attaching plate portion 50 30a of the butt member 30 is shown of single wall thickness, but both ends of the sheet could be extended to form a double wall thickness if desired. However, I find that by welding or otherwise joining the double walls of the parts 34-35, 60 a substantial hinge construction is formed.

65 It will also appear that a space 36 is formed between the arc-shaped portion 35 and the bearing 33 to receive the offset end 31a of the hood portion 31 of the butt part 29 in the swinging movement of the hinge butts one with respect to the other, as is indicated in dotted lines in Fig. 6 of the drawings. The butt members 29 and 30 are coupled together by a pintle pin 23 identical in all respects to the pin 23 shown in Figs. 1 to 4 inclusive. It is here to be noted that the curvature of the semi-cylindrical bearing portions 18 and 32 is greater than 180° to extend the folded edges 18a, 32a sufficiently above the pintle pin to prevent its displacement from said bearing.

75 However, I have shown in Figs. 8, 9 and 10, slight

modifications of the butt members 13, 29 respectively.

In Figs. 8 and 9, I have shown at 31 a butt member which is identical in general construction to the butt member 13 excepting that a tongue 38 portion 38 is cut from the material of the part 39 to form the bearing 40, which is a substitute for the bearing 18, a complete cylindrical bearing which is of less length than the complete bearing 40. The end portions 40a, note Fig. 9, 10 at each side of the tongue 38 are of the same cross sectional contour as that of the hinge butt 13 as shown in Fig. 4 of the drawings. The cut out in the part 39 forming the tongue 38 is indicated at 39a. In this connection, it will be understood 15 that all of the pintle bearings 40 of the butt member 37 may be of the same construction as that disclosed in Figs. 8 and 9. On the other hand, this construction may be employed only on predetermined bearings or on alternate bearings 20 throughout the complete hinge strip.

In Fig. 10 of the drawings, I have shown at 41 a butt member similar in general construction to the butt member 29 and to which is applied the structural principle incorporated in Figs. 8 and 9 25 of the drawings. In other words, the normal semi-cylindrical bearing 42 includes a projecting tongue 43 cut from the end portion 44 of the butt as indicated at 44a to provide a complete cylindrical bearing intermediate the ends of the bearing 42. With this type of hinge, each bearing 42 may be of the same construction or predetermined spaced bearings or alternate bearings may be of this construction and the others similar to the bearings shown on the butt 29.

35 With the construction shown in Figs. 8, 9 and 10, the companion butt members 14-30 will be employed or butt members similar to the butt member 45 shown in Fig. 11 of the drawings, which butt member differs from the members 40 40 14 and 30 primarily in eliminating the arc-shaped extensions 24-35 and substituting therefor on one part 46 of the hood an integral curved or arc-shaped portion 47 which forms a space 48 permitting the free travel of the butt 45 members one with respect to the other. The end of the portion 47 has a flange 49 for attachment to the attaching plate 45a of the butt 45, said plate being extended to provide this attachment. The butt member 50 in this construction may constitute any one of the butt members 13, 29, 37 or 41.

To illustrate one use of a companion butt member I have shown in Fig. 8 of the drawings a butt member 51 which is similar to the butt member 30 and includes a spacing or offset portion 52 and a curved or arc-shaped portion 53, the portions 52 and 53 being of double walled thickness, and may be welded or otherwise secured together. At the free end of the curved or arc-shaped portion is an angularly extending attaching plate portion 54 for attachment to the other part of the hood. At 55 I have indicated a pintle pin which passes through and couples both of the butts 37 and 51, the pintle pin 55 65 being of the same structure as the pin 23.

70 It will be noted that by arranging the flanges 10a, 11a of the hood parts at acute angles with respect to the adjacent walls of said parts, or in other words, in diverging relationship with respect to each other, sufficient clearance is provided for the butt members to permit the swinging movement of the hood parts into open position.

75 The hood portion of the outer butt member 75

forms a spacing and finishing strip between the adjacent edges of the hood parts or other swinging members to be coupled together by the hinge, whereas the inner butt member or the curved 5 arc-shaped portion thereof, for example, the portions 24—35 or the parts 41, Fig. 11, forms a trough for receiving any water that may pass between the separate butts of the hinge or between the butt and the opposed hood portion.

10 A hinge made according to the structures disclosed will be simple and economical in construction, as well as strong and durable in use. While the invention is shown applied to swinging members of specific character, it will be apparent 15 that the hinge may be used in coupling opposed swinging members of any kind or class, wherein it is desired to conceal the joint of the hinge as well as to provide a finishing strip between adjacent hinged edges of the swinging members.

20 It will be noted upon a consideration of the drawings that in the several forms of hinges disclosed, the pintle bearings are free from or in spaced relation to the walls of the outer hood portion as well as the channel or trough portion 25 of the hinge. In other words, the hinge parts or butt members are mounted and supported upon the pintle pin by the engagement of the pintle bearings therewith. Thus, it will be seen that the frictional engagement is between the pintle bearings and the pin and not between the other relatively movable parts, aside from the possible endwise engagement or abutment of the pintle bearings of one hinge part with those of an adjacent part.

30 Having fully described my invention, what I claim as new and desire to secure by Letters Patent, is:

1. In a hood hinge, an outer hinge part comprising a curved portion extending throughout 40 the length of said part and forming a finishing strip between the hood members to be joined by said hinge, one side edge portion of said part being fashioned to form a plurality of spaced pintle bearings disposed within said finishing strip, another hinge part having spaced pintle bearings 45 disposed intermediate the bearings of the first named part, a pintle pin mounted in the bearings of both parts to couple said parts together, the last named hinge part including a projecting attaching plate portion including an arc-shaped 50 trough disposed in spaced relation to the pintle bearings of said part, the pintle bearings of the second named part being cylindrical in form and the pintle bearings of the first named part being 55 of an arc greater than 180° and including projecting tongue portions forming cylindrical bearings intermediate the ends thereof.

2. A hinge construction comprising a pair of sheet metal hinge parts, one part being fashioned 60 to form spaced cylindrical pintle bearings with an extending attaching plate portion, the other part having a central curved hood portion extending throughout the length thereof, one edge of the hood portion terminating in an attaching plate 65 and the other edge portion being fashioned to form spaced pintle bearings disposed intermediate the bearings of the first named part, a pintle pin mounted in the bearings of both parts for coupling said parts together, the pintle bearings of 70 the second named part including a continuous strip extending onto the attaching plate of said hinge part, and the attaching plate of the first named hinge part joining the pintle bearings in an arc-shaped portion disposed in spaced relation to the bearings thereof.

3. A hinge comprising a pair of elongated hinge parts, each fashioned from elongated strips of sheet metal and having longitudinally spaced pintle bearings interfitting in edge to edge relation with the pintle bearings of the opposed hinge part, the central portion of the sheet metal strip forming one hinge part being fashioned to form a convex substantially semi-cylindrical hood portion and spaced concave semi-cylindrical portions arranged beneath the hood portion and continuous 10 with the edge thereof forming the pintle bearings of said part, the free side edges of the strip extending from the hood portion and said pintle bearings to form an attaching plate portion of double wall thickness, the pintle bearings of the 15 other butt part being formed intermediate the side edges of the sheet metal strip employed for constructing said part, and said last named part including a concave trough portion arranged in spaced relation to the pintle bearings through the 20 length of said part, said trough portion being of double wall construction.

4. A hinge comprising a pair of elongated hinge parts, each fashioned from elongated strips of sheet metal and having longitudinally spaced pintle bearings interfitting in edge to edge relation with the pintle bearings of the opposed hinge part, the central portion of the sheet metal strip forming one hinge part being fashioned to form spaced cylindrical bearings and a concave semi-cylindrical hood portion extending throughout the 25 length of said strip in close proximity to said bearings, and the side edges of said strip extending from said bearings and hood portion at one side of said part and being arranged one directly 30 upon the other.

5. A hinge comprising a pair of elongated hinge parts, each fashioned from elongated strips of sheet metal and having longitudinally spaced pintle bearings interfitting in edge to edge relation with the pintle bearings of the opposed hinge part, the central portion of the sheet metal strip forming one hinge part being fashioned to form spaced cylindrical bearings and a concave semi-cylindrical hood portion extending throughout 40 the length of said strip in close proximity to said bearings, the side edges of said strip extending from said bearings and hood portion at one side of said part and being arranged one directly upon the other, and the central portion of the strip 45 forming the other hinge part being fashioned to form spaced pintle bearings and the side edges of said sheet being folded one upon the other and fashioned to form a trough extending throughout the length of the hinge and in spaced 50 relation to said bearings.

6. In a hood hinge, an outer hinge part fashioned from an elongated strip of sheet metal, said strip intermediate the side edges thereof being fashioned to form an outwardly extending curved hood portion extending throughout the length of said part, the adjacent portion of the strip being cut and fashioned to form pintle bearings spaced longitudinally of and arranged within said hood portion, the side edges of said sheet being arranged one upon the other and extending from said hood portion and bearings to form an attaching plate portion for said hood part, and portions of said bearings being circumferentially continuous.

7. In a hood hinge, an outer hinge part fashioned from an elongated strip of sheet metal, said strip intermediate the side edges thereof being fashioned to form an outwardly extending curved hood portion extending throughout the length 70 75

of said part, the adjacent portion of the strip being cut and fashioned to form pintle bearings spaced longitudinally of and arranged within said hood portion, the side edges of said sheet being 5 arranged one upon the other and extending from said hood portion and bearings to form an attaching plate portion for said hood part, and the portions of said strip intermediate said bearings being arranged on the inner surface of said hood 10 portion.

8. In a hood hinge of the class described, elongated sheet metal hinge butts, one of said butts being fashioned to form a continuous curved hood portion with pintle bearings spaced longitudinally 15 of and arranged within the hood portion, the companion butt of the hinge being fashioned from an elongated strip of sheet metal fashioned substantially centrally thereof to form spaced cylindrical bearings, the side portions of the strip 20 extending from said bearings being arranged one directly upon the other and fashioned to form a curved trough arranged in spaced relation to and extending longitudinally of said bearings and an attaching plate portion at the free edge of said 25 trough.

9. A hinge comprising a pair of elongated hinge parts, each fashioned from elongated strips of sheet metal and having longitudinally spaced pintle bearings interfitting in edge to edge relation with the pintle bearings of the opposed hinge 5 part, the central portion of the sheet metal strip forming one hinge part being fashioned to form a convex substantially semi-cylindrical hood portion and spaced concave semi-cylindrical portions arranged beneath the hood portion and continuous 10 with the edge thereof forming the pintle bearings of said part, the free side edges of the strip extending from the hood portion and said pintle bearings to form an attaching plate portion of double wall thickness, the other hinge part 15 having an integral semi-cylindrical portion medially underlining the axis of the pintle bearings thereof and arranged in spaced relation to said pintle bearings, said portion extending throughout the length of said part with an attaching plate projecting from the edge of said semi-cylindrical portion, and a pintle mounted in the bearings of the hinge parts for coupling said hinge parts together.

JOSEPH SOSS. 25
